UNITED STATES PATENT OFFICE

CLARENCE C. DOUB, OF YORK, PENNSYLVANIA, ASSIGNOR TO THE FLOOROLA CORPORATION, OF YORK, PENNSYLVANIA, A CORPORATION OF DELAWARE

DESIGN FOR A FLOOR POLISHING MACHINE

Application filed March 26, 1931. Serial No. 39,257. Term of patent 3½ years.

To all whom it may concern:

Be it known that I, CLARENCE C. DOUB, a citizen of the United States, residing at York, county of York, and State of Pennsylvania, have invented a new, original, and ornamental Design for Floor Polishing Machines, of which the following is a specification, reference being had to the accompanying drawing, forming part thereof.

The figure is a perspective view of the floor-polishing machine, showing my new design.

I claim:

The ornamental design for a floor polishing machine, as shown.

CLARENCE C. DOUB.
